UNITED STATES PATENT OFFICE

FRANK W. HUDSON, OF ST. LOUIS, MISSOURI, ASSIGNOR OF ONE-TENTH
TO ARTHUR C. LAWDER, ONE-TWENTIETH TO JOSEPH E. GORMAN,
ONE-TWENTIETH TO PETER B. McCARTY, AND ONE-TWENTIETH TO
ARTHUR G. FRANCIS, OF ST. LOUIS, MISSOURI.

STEEL CAR-WHEEL.

No. 799,907.

Specification of Letters Patent.

Patented Sept. 19, 1905.

Application filed March 31, 1905. Serial No. 253,066.

To all whom it may concern:

Be it known that I, FRANK W. HUDSON, a citizen of the United States, residing at St. Louis, Missouri, have invented a certain new and useful Improvement in Steel Car-Wheels, of which the following is a full, clear, and exact description, such as will enable others skilled in the art to which it appertains to make and use the same, reference being had to the accompanying drawings, forming part of this specification, in which—

Figure 1 is an edge elevational view, partly in section, of my improved car-wheel. Fig. 2 is a side elevational view of the same, partly in section; and Fig. 3 is a detail view of one of the inserts.

This invention relates to a new and useful improvement in steel car-wheels, the object being to have the body portion of the wheel made up of soft steel, such as is usually employed in steel-casting plants, the tread and throat of the flange being made up in part of the soft steel of the body and the hard steel of inserts. These inserts may be of any character of hard steel to suit the tastes of the manufacturer and are first separately formed, as shown in Fig. 3, after which they are arranged around the mold and against the face of what would be the tread of the wheel in the mold, so that when the molten steel is poured into the mold it will flow around these inserts so that the inserts will be "cast in" the tread and throat of the finished wheel.

The inserts are preferably diagonally arranged, so that contact with the rail at all times will be made by at least two or more of said inserts, thus evenly distributing the wear over the tread and throat of the wheel.

Referring to Fig. 1, 1 indicates the body portion of a cast-steel wheel, and 2 indicates the insert of hard steel which is cast therein. This insert, as shown in Fig. 2, is preferably provided with a widened base portion, the contacting or upper face thereof being narrower than the bottom, so that when the molten steel flows around the insert the insert is practically dovetailed in position, thus making it impossible for the insert to have any play in its seat which would tend to work the same loose. In addition the insert is provided with a neck portion 3, curved corresponding to the throat between the flange and

tread of the wheel, and over this neck portion the soft steel extends, as indicated by the numeral 4. The inserts of course could be made in different shapes and be provided with other means for interlocking them with the body portion of the wheel; but I believe that the tapered faces shown will provide all the interlock that is necessary or required.

I am aware that changes in the construction, arrangement, and combination of the several parts of my device could be made and substituted for those herein shown and described without in the least departing from the nature and principle of my invention.

Having thus described the invention, what is new, and desired to be secured by Letters Patent, is—

1. In a car-wheel, the combination of a soft-steel body portion, and hard-steel inserts cast in the tread of the soft-steel body portion; substantially as described.
2. In a car-wheel, the combination of a soft-steel body portion, and diagonally-arranged hard-steel inserts inserted in the tread of the soft-steel wheel and flush therewith; substantially as described.
3. In a car-wheel, the combination of a soft-steel flange and tread, and hard-steel inserts whose outer faces are flush with the soft-steel tread, said inserts having a neck portion conforming to the shape of the throat between the flange and tread; substantially as described.

4. In a car-wheel, the combination of a soft-steel body portion, and hard-steel inserts arranged in the tread thereof, said inserts being provided with means for interlocking with the soft steel of the body portion; substantially as described.

5. In a car-wheel, the combination of a soft-steel body portion, and diagonally-arranged inserts anchored in the tread thereof, said inserts extending up around the throat of the wheel and being capped by an overhanging portion of the soft-steel flange; substantially as described.

In testimony whereof I hereunto affix my signature, in the presence of two witnesses, this 29th day of March, 1905.

FRANK W. HUDSON.
